Des. 191,763
Patented Nov. 14, 1961

191,763

SEARCH LIGHT OR THE LIKE

William W. Lee, 846 N. Humphrey Ave., Oak Park, Ill.

Filed Dec. 7, 1960, Ser. No. 63,140

Term of patent 14 years

(Cl. D48—32)

The dominant features of my design reside in the portions shown in full lines.

I claim:

The ornamental design for a search light or the like, as shown and described.
